US0D1048015S

(12) **United States Design Patent** (10) **Patent No.:** **US D1,048,015 S**
(45) **Date of Patent:** **** Oct. 22, 2024**

(54) **WEARABLE DATA CAPTURE DEVICE**

(71) Applicant: **CipherLab Co., Ltd.**, Taipei (TW)

(72) Inventor: **Chin-An Chou**, Taipei (TW)

(73) Assignee: **CIPHERLAB CO., LTD.**, Taipei (TW)

(**) Term: **15 Years**

(21) Appl. No.: **29/878,472**

(22) Filed: **Jun. 22, 2023**

(30) **Foreign Application Priority Data**

May 17, 2023 (TW) 112302450

(51) **LOC (14) Cl.** **14-02**

(52) **U.S. Cl.**

USPC **D14/427**

(57) **CLAIM**

The ornamental design for a wearable data capture device as shown and described.

DESCRIPTION

FIG. 1 is a top, front and right side perspective view of a wearable data capture device showing my new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1;

FIG. 8 is a top, rear and right side perspective view of the wearable data capture device; and,

FIG. 9 is a bottom, rear and left side perspective view of the wearable data capture device.

1 Claim, 9 Drawing Sheets
